G. C. LAURENCY

MEANS FOR FORMING THE FLEECE OR WEB IN CARDING MACHINES

Filed Nov. 2 1927

Fig.1.

Fig.2.

Inventor:

GUILLAUME CLEMENT LAURENCY.

By his Attorney: P. M. Mauday

UNITED STATES PATENT OFFICE.

GUILLAUME CLÉMENT LAURENCY, OF TWICKENHAM, ENGLAND, ASSIGNOR OF SIXTY
PER CENT TO GRANT MCLEAN, OF LA CASE, DIEPPE, FRANCE.

MEANS FOR FORMING THE FLEECE OR WEB IN CARDING MACHINES.

Application filed November 2, 1927, Serial No. 230,612, and in Great Britain October 26, 1926.

This invention relates to improvements in means for forming the fleece or web in carding machines.

It is known that the carding operation has for its purpose the disentangling of the locks of fibres by cleaning and separating the latter from each other.

When this operation is completed the fibres pass from the carding machine in the form of a fleece or web which is then wound in layers or condensed into sliver or rovings. In the formation of said web the fibres lose the parallelism which the carding action may have given them, and the purpose of the present invention is to preserve in the web this parallel position of the fibres obtained by the carding operation.

Broadly stated the invention consists in providing one or more rollers or cylinders which are designed to rotate about their individual axes and which, at the same time, advance over the section of the surface of the doffer cylinder that bears the fibres doffed from the card, in the direction of movement of the doffer and at a speed higher than the circumferential speed of said doffer in order to carry the ends of all the fibres forward on the hooks of the latter. Such arrangement is distinct from the mere application of a roller revolving on a fixed point of rotation.

The invention also comprises other features of construction, arrangement and combinations of parts as hereinafter fully described and claimed with reference to the accompanying drawing in which:

Fig. 1 is a partial elevation showing the main members of a carding machine which transform the fibres into a continuous fleece or web with the present invention applied thereto. Fig. 2 is a detail view showing driving and braking means for chains which carry the rollers or cylinders.

The fibres which are straightened and more or less parallelized between the hooks or teeth of the main cylinder A have their ends extending above said hooks when they reach the point C and they advance with said main cylinder until their said ends encounter the hooks of the doffer cylinder B. As the hooks of main cylinder A descend more rapidly than those of the doffer B the majority of the fibres turn round, and remain suspended on the hooks of doffer B as illustrated at D. In this position the fibres

regain their original undulations, as they are free, and, by describing a semi-circle with the hooks of doffer B, that portion of the fibres which is held by said hooks turns completely round whilst the free portion is folded at the rear, the result being that these fibres become folded and entangled in the fleece or web which is removed from the doffer B at the point F.

According to the present invention, the fibres suspended on the hooks of the doffer B are carried forward by rollers or cylinders 1, 2, 3 and 4, which are supported at their ends by chains 5 mounted at each side of and below the doffer B, the spindles of said rollers being capable of rotating freely in special links provided in said chains, whilst the latter pass over two pairs of toothed wheels or sprockets 6 and 7 mounted on two parallel axles 8 and 9 which extend from side to side of the machine.

By means of the axle 9 and its two toothed wheels, the chains are given a linear speed higher than the circumferential speed of the doffer B, and at each revolution the rollers which they carry enter one after another into contact with a different section of the surface of the doffer B. Owing to this contact the rollers roll over the surface of the doffer in the direction of movement of the latter.

This contact can be localized or adjusted at both ends of the rollers so that they do not touch the hooks of doffer B.

The number of rollers may vary and their speed decreases when they are more numerous.

In the position shown in Fig. 1, the roller 1 which has nearly finished its course over the periphery of the doffer B raises the last fibres of the sector subjected to its action, and the next roller 2 carries the fibres towards the doffer hooks before entering into contact with the latter. Owing to this alternate action of the rollers, the fibres suspended on the doffer are no longer folded at the rear, but are laid flat on the doffer in the direction of movement and extended forward at one end. The fibres are thus extended lengthwise in the fleece or web furnished by the carding machine and consequently also in the lap, sliver or roving.

The contact of the rollers 1, 2, 3, 4 with the doffer B is determined by the tension of the upper run of the chains, and this tension is itself determined by the resistance of

the axle 8. This resistance, which ensures the degree of contact of said rollers, can be obtained by various known means. In Fig. 2 a pulley 10 secured on the said axle 8 is surrounded by a brake band 11 from which is suspended a weight 12. The friction of this band increases the tension of the upper portion of the chains when the driving belt 13 rotates the axle 9 by means of the pulley 14. 10 What I claim as my invention and desire to secure by Letters Patent of the United States is:—

1. In a machine for carding textile fibres, the combination, with a doffer, of a plurality of rollers which advance, in the direction of movement of the doffer, over a section of the surface of the doffer which bears the fibres doffed from the card, carrier chains for said rollers located below the doffer, a pair of axles, driving and guiding sprockets fixed to said axles and engaged with said chains, and a brake device associated with one axle for adjusting the tension of the upper runs of the chains and, hence, the contact between the rollers and the doffer. 15

2. In a machine for carding textile fibres, the combination, with a doffer, of a plurality of rollers which advance, in the direction of movement of the doffer, over a section of the surface of the doffer which bears the fibres doffed from the card, carrier chains for said rollers located below the doffer, a pair of axles, driving and guiding sprockets fixed to said axles and engaged with said chains, and means for adjusting the tension of the upper runs of the chains and, hence, the contact between the rollers and the doffer. 20

3. In a machine for carding textile fibres, the combination, with a doffer, of a plurality of rollers which advance, in the direction of movement of the doffer, over a section of the surface of the doffer which bears the fibres doffed from the card, carrier chains for said rollers located below the doffer, a pair of axles, driving and guiding sprockets fixed to said axles and engaged with said chains, and a brake device associated with one axle for adjusting the tension of the upper runs of the chains and, hence, the contact between the rollers and the doffer. 25

4. In a machine for carding textile fibres, the combination, with a doffer, of a plurality of rollers which advance, in the direction of movement of the doffer, over a section of the surface of the doffer which bears the fibres doffed from the card, carrier chains for said rollers located below the doffer, a pair of axles, and driving and guiding sprockets fixed to said axles and engaged with said chains to move the chains at a linear speed which is higher than the circumferential speed of the doffer in order to carry the ends of all the fibres forward on the doffer hooks, said chains embodying special links wherein the pivots of the rollers are freely rotatable. 50

In witness whereof I have signed this specification.

GUILLAUME CLÉMENT LAURENCY.
